UNITED STATES PATENT OFFICE.

HERBERT E. WILSON, OF ANTRIM, NEW HAMPSHIRE.

LUG STRAP OR PICK-ARM STRAP FOR LOOMS.

Application filed January 8, 1926. Serial No. 79,974.

This invention relates to lug straps or pick arm strap for looms and has for its object to provide a novel pick arm strap in which the plug in the bend or bight of the 5 U-shaped body is so constructed as to give increased length of service over the plugs which are commonly employed. In one familiar form of lug strap the plug is made entirely of fabric, a strip of fabric being 10 rolled up to form a roll and then subjected to the action of dies to give it a shape to fit the bend of the body portion and also to give the wear face thereof a concave curvature, said plug being suitably anchored in 15 the body by means of a rivet.

While the all-fabric plug has the requisite hardness and density to make it acceptable for use in a lug strap or pick arm strap, yet it has the disadvantage that the fabric 20 does not withstand the wear to which the plug is subjected in the operation of the loom, and as a result the face of an all-fabric plug which engages the shackle of the pick arm soon wears down to a point where 25 the anchoring rivet is exposed, thus rendering the pick arm strap unfit for further use.

In an effort to increase the length of life 30 of the plug I have developed the present invention in which the plug of the pick arm strap is made up of alternate layers of fabric and leather. The presence of the fabric in the plug gives it the requisite hardness or density and the presence of the leather 35 introduces a wear-resisting element which will resist the wear to which the plug is subjected to a much greater degree than fabric and thereby increase the length of life 40 of the plug.

In order to give an understanding of the 45 invention I have illustrated in the drawings a selected embodiment thereof which will now be described after which the novel features will be pointed out in the appended claims.

In the drawings, Fig. 1 is a perspective view of a lug strap or pick arm strap embodying my invention;

Fig. 2 illustrates how the plug is formed; 50 Fig. 3 is a sectional view on substantially the section 3-3, Fig. 1.

In the drawings 1 indicates the usual U-shaped body of the lug strap or pick arm strap which is made of layers of fabric compacted together in the usual way. Situated 55 within the bend or bight of the body is the

usual plug 2, said plug having an exterior face 3 to fit the curvature of the inner face of the body 1 and having a concave wear face 4 which engages the shackle of the pick 60 arm. The plug is anchored in the body member by means of the rivet 5 which extends transversely through the plug and body member as usual.

The part of the lug strap or pick arm 65 strap which first wears out is usually the plug. It is a desideratum that the plug should be relatively hard and non-yielding and it has been found that a plug made of layers of fabric compacted firmly together 70 has the desired strength and hardness but such a plug has only inadequate wearing qualities and will soon become so worn on the wear face as to expose the anchoring rivet. 75

In order to provide a plug which has the requisite strength and rigidity to meet the requirements of use and which has also superior wearing qualities I have produced a plug which is made of alternate layers of 80 fabric and leather compacted firmly together. The presence of the fabric in the plug gives it the strength and rigidity required and the presence of the leather adds 85 the desirable wearing qualities. 85

One way of making my improved plug is to take a strip of fabric 6 and another strip of leather 7 and unite them adhesively and roll them into a roll as indicated at 8. This roll is then subjected to the action of dies 90 which subjects it to high pressure and firmly compacts the material and also gives it the desired shape with the convex exterior face 3 to fit the bend of the pick arm strap and the concave wear face 4. A plug having 95 this construction presents alternate layers of fabric and leather which are firmly compacted together and in making the plug I will preferably make the exterior layer of leather so that the wear face 4 of the 100 plug is a leather face. The plug when thus made is anchored in the pick arm strap body by means of the rivet 5 as usual.

The wearing qualities of leather in an article which is subjected to the kind of 105 wear to which a pick arm strap is subjected is greatly superior to that of fabric, but leather of itself has too much give or resilience to make a successful plug for a pick arm strap. By combining the leather with 110 the fabric, however, a plug having sufficient strength and rigidity is provided while at

the same time there is sufficient leather in the plug to give the additional wearing qualities and consequently a longer life.

When the pick arm strap is in use the leather wear surface will glaze over and produce a surface which will last a long time. When, however, the outside layer of leather on the wear surface finally wears through to expose the layer of canvas and the fabric layer then wears through, a second layer of leather will be exposed which will give another long term of service before it is finally worn through. With this construction, therefore, several layers of leather are provided which must be worn through before the plug is worn to such an extent that the pick arm strap must be discarded.

A pick arm strap embodying this invention can be made substantially as cheap as a pick arm strap with an all-fabric plug and it not only has all the advantages of the pick arm strap with the fabric plug,

but it also has the added advantage of a greatly increased length of life.

I claim:

1. A pick arm strap comprising a U-shaped body member and a plug anchored in the bend of the body member, said plug being formed of a large number of relatively thin layers of fabric and leather arranged alternately, the layers on the portion of the plug exposed to the wear of the picker stick lying substantially parallel to the wear face.

2. A pick arm strap comprising a U-shaped body member and a plug anchored in the bend of the body member, said plug being formed by alternate layers of fabric and leather with the leather layer forming the wear face of the plug.

In testimony whereof, I have signed my name to this specification.

HERBERT E. WILSON.
